UNITED STATES PATENT OFFICE.

JOHN B. TAYLOR, OF SCHENECTADY, NEW YORK, ASSIGNOR TO GENERAL ELECTRIC COMPANY, A CORPORATION OF NEW YORK.

SYSTEM FOR THE PREVENTION OF ELECTROLYSIS.

1,191,627.

Specification of Letters Patent. Patented July 18, 1916.

Application filed January 4, 1915. Serial No. 521.

To all whom it may concern:

Be it known that I, JOHN B. TAYLOR, a citizen of the United States, residing at Schenectady, in the county of Schenectady, 5 State of New York, have invented certain new and useful Improvements in Systems for the Prevention of Electrolysis, of which the following is a specification.

My invention relates to a system for the 10 prevention of electrolysis, and more particularly to such a system designed for use with electric railways in order to prevent electrolytic corrosion of earthed metallic structures adjacent the tracks.

15 Electric railway systems commonly utilize their rails as return conductors, but if the current is large the voltage drop therein becomes excessive, operating conditions are unsatisfactory, and part of the current 20 is diverted as stray current through the ground, where it seeks neighboring earthed conductors of low resistance, such as water and gas pipes. The flow of current in these pipes results in electrolytic corrosion at the 25 joints of the pipes and at those points where, because of their relative potential, current leaves the pipes to return through the surrounding earth to the adjacent rails and the generator. As is well understood, a consider- 30 able potential difference may exist between remote points of the earth's surface, and any such difference will be accentuated by the presence of such earthed conductors as the rails of an electric railway. Because 35 of these potential differences, it is impossible to say that a conductor carefully earthed at any single point is at "true earth" potential more truly than a similar conductor at some other point. It should be 40 theoretically possible, however, to determine the potential difference between any particular point and "true earth" by taking true earth as the average of the potentials of a large number of remote points. For the 45 purpose of the problem, it will undoubtedly be satisfactory to consider "true earth" as the potential of a point sufficiently remote from local distribution systems and similar disturbing influences so that it is practically

unaffected thereby. With reference to this 50 datum point or potential level, it will be found that both the rails and pipes will be at a lower potential at points near the power-house, and at a higher potential at points near the end of the line. With refer- 55 ence to each other, the pipes will be at a higher potential than the adjacent earth and rails at points near the power-house, while at distant points the pipes will be negative to the adjacent earth and rails. It is, therefore, desirable to correct these conditions in such a way that the pipes shall be kept at the same potential as that of the adjacent earth, and also be kept at "true earth" po- 60 tential difference between different points 65 in the pipes. If these results can be obtained, flow of current from pipes to rails and across pipe joints can be prevented.

Various methods have heretofore been proposed by means of which a partial cor- 70 rection is possible. If, for instance, the pipes are kept at the same potential as the adjacent rails by bonding at frequent inter- 75 vals, trouble will result from current leav- ing the pipes for earth return and from flow 80 across the joints of the pipes. If both pos- itive or outward and negative or return feed- 85 ers are provided, leading from the power- house to a remote point, then a booster may be inserted in the return feeder and excited 90 from the positive feeders so that current will be diverted from the rails in an amount proportional to the load at that point. At any event, this scheme presupposes that the return current at any one point is propor- 95 tional to the power supplied to that point, whereas in a complex system it is unlikely that such a relation will exist. It has also been proposed to insert a resistance in one or more of the return feeders of a system in order to equalize the drop therein. The potential of the various points of connec- tion of the return feeders to the rails is thereby equalized, and the potential differ- ence between any two points is minimized. 95 The successful operation of this arrange- ment, however, depends on a distribution of the load substantially the same as that for

which the feeder resistances are designed and on holding the negative bus bars below earth potential. Obviously, also, there must be an energy loss in these resistances.

6 The object of my invention is, then, to devise an arrangement applicable to electric railway systems, whereby these difficulties may be avoided and electrolysis practically eliminated.

10 Another object is to devise an arrangement whereby the conductivity of the rails may be fully utilized and return feeders avoided.

15 Still another object is to devise a system so controlled that the desired conditions are maintained regardless of load conditions.

I attain these results by dividing the track into a plurality of sections insulated from one another, interpolating a source of E. M. F., between said insulated sections and controlling this E. M. F., by means of a regulator responsive to the potential difference between points in adjacent sections of the track so that the interpolated E. M. F. is essentially equal to the potential drop of the adjacent section, and that there is no difference of potential between the points where the regulator is attached.

20 One embodiment of my invention is illustrated in the accompanying drawing in which—

25 Figure 1 is a diagrammatic view representing a portion of an electric railway having my system applied thereto. Figs. 2 and 3 are diagrams showing the potential gradients of the various conductors before and after the application of my system to an electric railway.

30 In Fig. 1, a generator 10 is illustrated as having its positive terminal connected to a trolley 11, by means of which power is applied to cars, such as indicated at 12, and the rail 13 is used as the return conductor and connected to the negative terminal of the generator. The rail is divided into sections 15, 16 and 17, of any desired length, by means of insulated joints. Buried in the ground near the rails is a line of pipes 18. A source of electromotive force is then 35 interpolated in the rail to by-pass the insulated joints and assist the flow of current toward the generator. This source may take various forms, but will conveniently be in the form of a dynamo-electric machine 20, ordinarily termed a booster. This booster may be driven by means of a motor 21 supplied with power from the railway circuit, and may have its field separately excited from an exciter 22 mounted on the same shaft with the booster. As previously described, it is desired that the electromotive force interpolated by means of this booster should be essentially equal to the drop in the adjacent rail sections, and that this relation shall hold, regardless of load conditions. I

have, accordingly, shown one form of regulator comprising a magnet coil 31 responsive to the potential difference between remote points in two sections, such as the points *a* and *b* of the sections 15 and 16. This regulator is arranged to short-circuit a resistance 32 in circuit with the exciter field, by attracting a pivoted armature 33 against a fixed contact when there is a potential difference between the points *a* and *b* large enough 70 to energize the coil 31. The armature 33 is normally held away from the fixed contact by means of a spring until the coil 31 is energized to a predetermined strength. This arrangement is duplicated at each of the insulated joints between adjacent sections, and, obviously, the types of apparatus here shown are only one of several well-known arrangements which would be equally applicable.

85 In Fig. 2 I have illustrated by means of a diagram the conditions found in a simple system with an evenly distributed load before the application of my system. In this diagram as well as in Fig. 3, the ordinates 80 represent voltages, and the zero point is taken as the potential of the negative terminal of the generator. The abscissæ represent distances from the generator. The gradient *T* may be taken to represent the 95 potential of the trolley, having, as it will, a gradual decreasing voltage toward the end of the line, while the horizontal line *T E* is the datum level which I have termed “true earth”. The potential gradient *R* of the 100 rails carrying the return current starts at the negative terminal of the generator, and theoretically maintains a constant slope to the extreme end of the line. At points remote from the generator any metallic 105 earthed conductors, of which the commonest form is a pipe system, will be negative to the rails, while at points near the generator these pipes will be positive to the rails and to the surrounding earth. At the same time 110 it has been found that the potential of both rails and pipes is above the potential of true earth at points remote from the generator, and below the potential of true earth at points adjacent to the generator. The potential 115 gradient *P* of the pipes in this simple case will also have a constant slope, since stray currents leaving the rails at remote points will be taken up by the pipes, and, passing through their length, will be delivered up to 120 the rails at points near the power-house. Electrolytic corrosion will, accordingly, be caused at those points where the potential of the pipes is sufficiently above that of the rails to cause a flow of current between the 125 two.

130 If my system of prevention is now applied in this simple case, the resulting conditions will be illustrated by Fig. 3. The gradients *T* and *T E* will retain the same slopes

as in Fig. 2, although the position of T E with respect to the potential of the negative terminal of the generator is changed. At its point of connection with the generator, the rail must be at the potential of the negative terminal of the generator, and hence will be represented in the diagram as at zero volts. The gradient R_{15} , representing condition in rail section 15, will have the same slope as the gradient R in Fig. 2. At the insulated joint between sections 15 and 16 I have interpolated an electromotive force B_1 , which is generated by the corresponding booster 20, thus causing an abrupt change in the rail gradient, and which is here shown as bringing the potential of the near end of the next section down to a value approximately the same as that of the negative generator terminal. Proceeding with the analysis it will be seen that the rail gradient R_{16} will then be extended in a parallel direction to the gradient R_{15} for a distance corresponding to the section 16, where another abrupt change will be caused by the interpolated electromotive force B_2 , as in the previous case. The diagram will be duplicated as many times as there are insulated joints and interpolated voltages thus giving the gradient R_{17} and the interpolated E. M. F. B_3 . Under these conditions it will be found that the potential of the negative terminal of the generator will be nearer true earth potential, and that true earth potential will be approximately at the potential of the mid-point of any rail section. The result is that the potential difference between true earth and any point in the return rail is greatly minimized and that there is practically no potential difference between the pipe and true earth, and, consequently, no potential difference between various points in the pipe. It will, therefore, be seen that there will be no stray currents of any magnitude flowing from the rails to the pipes, nor from the pipes to the rails, and that there will be no flow of current across the pipe joints.

The regulator coil 31 is shown as connected to approximately the mid-points of the rail section, and from a comparison of Fig. 1 and Fig. 3 it will be seen that under ideal conditions there will be no potential difference across this coil, and hence no current flow therein. If, however, the actual conditions of practice cause a potential difference to exist, then the resistance 32 will be short circuited, and the field current of the exciter and of the booster will be increased. This will correspondingly increase the interpolated voltage and restore conditions so that they will be correctly represented by the diagram in Fig. 3. This regulator will preferably be of the vibrating type and so designed that it will maintain a constant potential difference between the points

to which the coil 31 is connected. Obviously, some potential difference must exist before the armature 33 can be attracted, but the magnitude of this potential will be determined by the design of the apparatus, and will approach closely the theoretical conditions which it is desired to maintain. By means of interpolating voltages between the rail sections I am also enabled to fully utilize the conductivity of the rail for the return current and to thereby avoid the use of expensive return feeders.

As will be readily understood, the conditions obtained in practice are so complex that the diagrams here shown will never exactly represent the true state of affairs. For all practical purposes, however, my analysis is sufficient, and by the use of a regulator operated in the manner described any variation may be compensated.

Although I have herein illustrated what I conceive to be a practical and desirable form of my invention, I realize that the same result can be obtained by other well known apparatus, and I, therefore, do not desire to be limited to the exact arrangement shown and described, but seek to cover in the appended claims all those forms which come within the true scope and spirit of my invention.

What I claim as new and desire to secure by Letters Patent of the United States, is:—

1. In combination, a current carrying conductor divided into sections, a source of E. M. F. interpolated between two sections of said conductor, and means responsive to the difference in potential between fixed points in said conductor for regulating the E. M. F. of said source.

2. In combination, a current carrying conductor divided into sections, a source of E. M. F. interpolated between two sections of said conductor, and means for regulating the E. M. F. of said source so that the potential difference between fixed points in two sections is minimized.

3. In combination, a current carrying conductor divided into sections, a source of E. M. F. interpolated between two sections of said conductor, and means for regulating the E. M. F. of said source to maintain a constant potential difference between fixed points in two sections of the conductor.

4. In combination, a current carrying conductor divided into sections, a source of E. M. F. interpolated between adjacent sections, and means for controlling said source in response to the potential difference between substantially the mid points of said sections.

5. In combination, a current conductor, earthed throughout practically its entire length, points of said conductor being at a different potential than the adjacent earth, means for minimizing the escape of current

from said conductor to earth comprising a plurality of sources of E. M. F. interpolated in said conductor at intervals, and means for regulating the E. M. F. of each source to 5 minimize the potential difference between all points of said conductor.

In witness whereof, I have hereunto set my hand this 2nd day of January, 1915.

JOHN B. TAYLOR.

Correction in Letters Patent No. 1,191,627.

It is hereby certified that in Letters Patent No. 1,191,627, granted July 18, 1916, upon the application of John B. Taylor, of Schenectady, New York, for an improvement in "Systems for the Prevention of Electrolysis," an error appears in the printed specification requiring correction as follows: Page 1, line 65, before the word "difference" insert a comma and the words, *so that there shall be no potential;* and that the said Letters Patent should be read with this correction therein that the same may conform to the record of the case in the Patent Office.

Signed and sealed this 22d day of August, A. D., 1916.
